FREEZE-PROOF RADIATOR

Samuel Schenkel, Brooklyn, N. Y.

Application June 7, 1952, Serial No. 292,265

2 Claims. (Cl. 257—151)

1

My invention is an improvement in radiators, particularly radiators that are parts of steam heating systems.

An important object is to provide a radiator that is freeze-proof; and to this end the radiator, which may be of the usual type comprising vertical sections secured together, is so constructed that the sections communicate with one another at progressively lower points in the direction of the outlet pipe. Hence no water is ever trapped in the radiator, and any water of condensation will drain out and be returned to the steam generator.

Other objects and advantages are made clear in the following description, taken with the accompanying drawings, which illustrate the best form of my invention now known to me. But this disclosure is explanatory only and variations in structural details may be adopted without omitting or deviating from the essential characteristics defined in the appended claims.

On said drawings,

Figure 1 is a longitudinal vertical section of a radiator according to this invention, and

Figure 2 is an end elevation.

The radiator is made up of hollow sections 1, and it is supported on short legs 2, which are formed on the bottoms of the sections at the two ends of the radiator, only one of said end sections being shown. The inlet pipe for steam is shown at 3, connected to the upper part of one end section, and the outlet pipe 4 is coupled to the section at the opposite end. The radiator has the usual air vent 5, kept closed by a screw plug 6.

The exhaust pipe 4 is always coupled in any suitable manner to one of the sections at the end of the radiator and steam condensing in the radiator flows through it back to the boiler of the heating system. The supply pipe 3 is usually connected to the opposite end of the radiator, but in some systems, this pipe 3 is omitted and the pipe 4 serves both to supply the steam to the radiator and drain the water from it.

In most radiators the bottom surfaces of the inside chambers in the sections are all at the same level. Water of condensation collects thereon; and if the temperature drops too much, as in unusually cold weather, it may freeze in the lower parts of the sections before running off at the pipe 4. In some installations the radiator is set up in a tilted position, with the sections so inclined that the end section connected to the pipe 4 is lowest, to ensure full drainage

2

and avoid freezing; which is apt to cause the sections to burst and leak at the lower portions.

With my invention freezing and damage are prevented by making the bottom surfaces of the interior spaces in the sections slope gradually toward the section at one end to which the pipe 4 is coupled. The section 1 at the left on Figure 1 with the legs has an inside space with a sloping bottom surface leading to an aperture 6 that is in line with an opening 7 in the adjacent side of the next section 1a. This opening 7 has an outside boss 8 with an inside shoulder 9, and surrounding the opening 6 is a boss 10 with an outside shoulder 11. The rim of the boss 10 telescopes into the boss 8 and abuts the shoulder 9, while the rim of the boss 8 encircles the rim of the boss 10 and abuts the shoulder 11. The joint is sealed by any suitable means.

Similarly the section 1a is joined to the next section 1b through an opening 6 in the section 1a and an aligned opening 7 in the section 1b, with interfitting bosses 8 and 10 as before. The openings through which the sections 1a and 1b communicate are somewhat lower than the openings through which the sections 1 and 1a are in communication; and so on to the last section coupled to the pipe 4. The sloping bottoms of the interior spaces in the sections and the sloping interior surfaces of the coupled bosses 8 and 10, the axes of said openings and the bosses surrounding them being inclined to the same extent, make a duct or channel that is straight and smooth along the bottom of the radiator, when the sections are upright and vertical, so that all condensed water will naturally flow down to the pipe 4, even if the heat is turned off and the temperature falls below freezing. The radiator is thus always drained of any liquid water and freezing cannot take place.

The sections have the usual shape, being open with large apertures at the middle with spaces 12. Each section has perforated projections 13 in the space 12 for rods 14, the ends of which are threaded to receive nuts to hold the sections together.

Having described my invention, what I believe to be new is:

1. A radiator comprising hollow sections placed side by side, the section at one end of the radiator having an outlet opening in its lower portion on one side and the remaining sections each having in its lower portion an inlet opening at one side and an outlet opening at the other side, the inlet and outlet openings being respectively at increasingly lower points on each

section from said one end of the radiator to its opposite end, the inside bottom surfaces of each section being inclined and flush with the lower edges of said openings, the sections having interfitting bosses coupling the sections together and surrounding said openings with the inlet opening of one section registering with the outlet opening of an adjacent section, the axes of said bosses also having the same inclination, so that said bottom surfaces form a sloping drain channel through said openings at the bottom of said radiator to the lowest of said outlet openings thereof.

2. A radiator comprising hollow sections placed side by side, the section at one end of the radiator having an outlet opening in its lower portion on one side and the remaining sections each having in its lower portion an inlet opening at one side and an outlet opening at the other side, the inlet and outlet openings being respectively at increasingly lower points on each section from said one end of the radiator to its opposite end, the inside bottom surfaces of each section being inclined and flush with the lower edges of said openings, the sections having in-

5 terfitting bosses coupling the sections together and surrounding said openings with the inlet opening of one section registering with the outlet opening of an adjacent section, the axes of said bosses also having the same inclination, so that said bottom surfaces form a sloping drain channel through said openings at the bottom of said radiator to the lowest of said outlet openings thereof, said sections being of equal
10 height with their outside bottom surfaces substantially in flush horizontal alignment and being open in the middle with large central apertures, and having lugs at the upper and lower edges of said apertures for tie bolts to secure
15 said sections in assembled relation.
